UNITED STATES PATENT OFFICE.

KAARLO ENGELBERT SALOVAARA, OF JYVÄSKYLÄ, FINLAND, RUSSIA, ASSIGNOR TO
FIRM AKTIEBOLAGET FREDR. WAGNER, OF STOCKHOLM, SWEDEN.

MAILING-MACHINE.

1,178,182.

Specification of Letters Patent.

Patented Apr. 4, 1916.

Application filed March 5, 1914. Serial No. 822,773.

To all whom it may concern:

Be it known that I, KAARLO ENGELBERT SALOVAARA, a citizen of the State of Finland, residing at Jyväskylä, Russia, have invented 5 certain new and useful Improvements in Mailing-Machines, of which the following is a specification.

The names and addresses are labeled on newspapers, in Finland as well as in other 10 countries, first being printed on a sheet of paper, cut apart, gummed and by hand fastened on each paper. Another way is to cut long strips from printed sheets on which the addresses are printed one after 15 the other, these strips being put in a machine driven by hand. The strips are directed by hand over a roller wetted with gum to a cutting apparatus, where the strip is cut off and the cut piece is fastened on 20 the newspaper at its proper place. This work requires much time and trouble and is a great annoyance when tens of thousands of papers have to be addressed in two or three hours' time.

25 In the machine invented by me the address is printed directly on the newspaper from the address lines, which are put together in the composing machine. The address lines are arranged in suitable galleys 30 or races. Each address contains the same number of lines, either one, two or more. The lines are conducted into the machine, which automatically separates the lines belonging to each address, and prints the address on the newspaper, which is carried at the same time in the machine. The used lines are carried away by the machine automatically in the same order, as are also the 35 newspaper.

40 The machine can be driven by foot and the newspaper put in by hand, but when greater speed than three to four thousand an hour is wanted, the machine may be connected with a paper feed machine and 45 driven by a motor, or else may be connected directly with the printing machine.

Besides for addressing newspapers, the machine may be used to print addresses on envelopes, etc.

50 In the accompanying drawings, showing by way of example, one embodiment of the invention, Figure 1 is a side elevation of the machine; Fig. 2 is a plan, certain parts being not shown; Fig. 3 is an end elevation, 55 and Fig. 4 is a diagrammatic side view showing the means for conveying the pa-

pers to be addressed to the printing mechanism.

The machine comprises the following parts: The galley 1 along which the address lines pass to the printing mechanism. The bottom of this galley consists of an endless thin sheet iron band 10', disposed around the pulleys 2 and 3, which by means of a belt receive their motion from the pulley 4. Said band moves slowly along, carrying the address lines to the end of the galley 1. A lever 5 is moved to its normal position by the eccentric 6, against the action of a spring 7 which causes the lever and the piece 8 which is fastened at its end to move so that the piece 8 is pushed transversely into the galley, from which it pushes the address lines, through an adjustable opening at the side of the galley, to the space 70 between the jaws 9 and 10. The piece 8 is removable and may be replaced by other pieces adapted to the thickness of 1, 2, 3, or more address lines, which number it will push into the space between the jaws 9 and 10. The spring 11 presses the jaws 9 and 10 toward each other, at the same time clamping the lines therebetween. When the lines are again about to be replaced by other lines, the jaws are separated by means of the eccentric 12, which engages the end of the bar 13 and so draws the jaw 9 away from the jaw 10. A race 14 leads the address lines away from the printing mechanism. A block 15 which, through the influence of the spring 16 is pushed into the race 14, causes the lines to move along after they have come into the race from between the jaws 9 and 10. An eccentric 17 draws the block 15 back to its normal position by 85 means of a bent rod 18 movable in a fixed bearing 61. A hammer apparatus 18, to the head of which is connected the stamper 19, adjustable by means of screws and springs, presses the newspaper against the 90 address lines between the jaws 9 and 10. The stamper is carried on a bent lever 80. A spring 20 acting on the lever 80 keeps the hammer apparatus raised, and an eccentric 21 produces the aforesaid pressing. Around pulleys 22, 23, 24, 25, 63 and 64 are drawn strings 62 and 65, which carry the newspapers over the machine after they have been taken from the table and put between the strings either by hand or by 105 a special paper feed machine. Weights 27 and 28 attached to rollers keep the strings 110

stretched. A belt 29 transmits rotary motion from the pulley 30 to the pulley 64 which moves the strings 62. A wing 31 mounted on a shaft 69 is kept in a vertical position by the spring 32. The wing is thus held between the conveying strings so that each newspaper is stopped against the wing until the lever 33 through the influence of the eccentric 6 pulls the string 68 which is fastened thereto, and whose other end is wound around the shaft of 31, thus drawing the wing 31 to a horizontal position and permitting the newspaper to pass to a similar wing 34. There the newspaper again stops until the hammer 18 and the stamper 19 have performed the aforesaid pressing. Then the lever 35 through the influence of the eccentric 36 draws the wing 34 to a horizontal position so that the paper is free to pass to the stop 37. From this the paper is pushed by the wing 38, which gets its motion through the lever 39 from the eccentric 40.

The shaft 41 on which the aforesaid eccentric as well as the pulleys 42 are fastened gets its motion from the pulley 44 on the shaft 43. To the flywheel 45 is fastened the treadle 46. A belt may be put around the flywheel if the machine is connected to a motor. By means of a friction clutch 47, part of the machinery may be stopped without stopping the motor. A color ribbon passes from a roller 48 to the roller 49. A lever 50 connected with the bar 13, turns the roller 49, which winds the color ribbon upon itself. The address lines are pushed into the galley 1 from a table 51 while a table 52 receives the lines from the race 14.

The machine works as follows:—The address lines move along the galley 1 to the end thereof being conveyed by the moving bottom of the galley. Supposing that each address contains two lines, the piece 88 corresponds to this width. The spring 7 through the lever 5 causes the piece 8 to move in the direction indicated by the arrow. Then the piece 8 pushes in front of itself two lines from the galley 1 through the opening on its side, the opening being so wide that two lines easily may pass, but not more, into the space between the jaws 9 and 10, the jaw 9 having already through the influence of the eccentric 12, been drawn away from the jaw 10, so that the lines easily can come between the jaws. After this the eccentric 12 ceases to act, and the spring 11 causes the jaw 9 to clamp the lines between it and the jaw 10. At the same time newspapers are conveyed, either by hand, by means of a paper feed machine or directly from the printing machine between the conveying strips to the front of the wing

31, this wing through the influence of the lever 33 and eccentric 6 is raised in a horizontal position, thus permitting the conveying strings to carry the newspaper to the wing 34. Then the eccentric 21 engages the lever of the hammer apparatus 18, causing the stamper 19 to press the newspaper and the color ribbon under the same against the jaws 9 and 10 and the address lines between them whereby on the paper there is made a print of the address lines and the jaws 9 and 10. The prints of the jaws on each side of the address lines form broad ink lines, making the address more noticeable. After this printing is performed, the stamper is raised and simultaneously the wing 34, and the paper, conveyed by the strings, arrives at the stop 37, whence the wing 38 pushes the papers. The shaft 41 has now made a complete rotation and the respective springs and eccentric have drawn all the parts moved by them to their original positions. On its second turn again the eccentric 12 causes the space between the jaws 9 and 10 to be widened, simultaneously the piece 8 pushes the two lines which have moved to the front, in between the jaws, from where the former lines through the lines coming behind, are pushed into the race 14, after which the block 15 pushes the lines so much ahead, that the lines between the jaws again are free to pass to the race 14. At the same time the above described motion has continued.

I claim as my invention:

In a mailing machine, the combination of a galley for the address lines; a pair of jaws adapted to receive print lines therein; a piece adapted to push the address lines from the galley into the space between said jaws; a race adapted to receive lines from between said jaws when pushed out by incoming lines from said galley; a block in said race; an endless band forming the bottom of said galley; a stamper over said jaws and the lines therebetween; a shaft passing transversely beneath the said galley; operative connections between said shaft and the endless band, said piece, said block and said stamper; conveying strings for placing the papers beneath said stamper; a wing operated from said shaft for stopping the papers under the stamper; and a clutch on said shaft between said connections and the wing operating means.

In testimony whereof, I have affixed my signature in presence of two witnesses.
